(57) **CLAIM**

The ornamental design for a beauty lamp, as shown and described.

DESCRIPTION

FIG. 1 is a front, right and top perspective view of a beauty lamp, showing my new design;

FIG. 2 is a rear, left and bottom perspective view thereof;

FIG. 3 is a rear, left and bottom perspective view of the beauty lamp shown in an alternate configuration of use;

FIG. 4 is a front view of the beauty lamp of FIG. 1;

FIG. 5 is a rear view thereof;

FIG. 6 is a left side view thereof;

FIG. 7 is a right side view thereof;

FIG. 8 is a top view thereof;

FIG. 9 is a bottom view thereof; and,

FIG. 10 is an enlarged view of the portion marked 10 in FIG. 1.

The broken lines shown in the drawings illustrate portions of the beauty lamp that form no part of the claimed design.
